US0D1064885S

(12) **United States Design Patent** (10) **Patent No.:** **US D1,064,885 S**
(45) **Date of Patent:** **** Mar. 4, 2025**

(54) **WIND CHIME SUPPORT**

(71) Applicant: **Changwen Su**, Lingui (CN)

(72) Inventor: **Changwen Su**, Lingui (CN)

(**) Term: **15 Years**

(21) Appl. No.: **29/843,234**

(22) Filed: **Jun. 20, 2022**

(30) **Foreign Application Priority Data**

Dec. 31, 2021 (CN) 202130877242.X

(51) **LOC (15) Cl.** **10-05**

(52) **U.S. Cl.**

USPC **D10/118.1; D10/118**

(57) **CLAIM**

The ornamental design for a wind chime support, as shown and described.

DESCRIPTION

FIG. 1 is a first perspective view of a wind chime support showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of wind chime support that form no part of the claimed design.

1 Claim, 8 Drawing Sheets
